SEALING MACHINE.

Application filed October 3, 1928, Serial No. 309,982, and in Great Britain May 5, 1927.

This invention relates to sealing machines and has particular reference to a machine for supplying, automatically vacuumizing containers, and then sealing them in rapid succession.

The chief object of the present invention is to provide an improved form of machine assuring exhausting or vacuumizing the container before the cap is sealed thereon, and a further object is to construct a machine for varied operation as regards vacuumizing period which will always operate so that sealing is effected only after a proper vacuumizing obtains.

Various other objects and advantages will be apparent from the following description of an embodiment of the invention, and the novel features will be particularly pointed out hereinafter in the appended claims.

In order that the invention may be clearly understood reference will now be made to the accompanying drawings which show a preferred construction by way of example and in which like reference numerals designate the same or similar parts.

Fig. 1 shows in sectional elevation a machine in which a hand lever causes a platform to rise to a vacuum chest and control the pressures therein for vacuumizing and sealing a container.

Fig. 2 is a sectional elevation on the line II—II of Fig. 1 showing the construction by which the means of operating the platform is utilized to control the operation of the diaphragm in the vacuumizing chest.

Fig. 3 is a detail elevation, partly diagrammatic, showing the connections between the valve chambers, and atmosphere and the reduced pressure by which the container is vacuumized, hereafter referred to; and Fig. 4 is a plan view of said connections.

Referring first to Fig. 1 and considering the construction to be utilized in applying a closure of the type having curled tongues by which it is attached to a container, the apparatus includes a moving head comprising a presser member 1 and a coaxial cup like member 2. The presser member 1 is formed with an axial rod 1^a about which is a spring 3 located between the presser member 1 and a sleeve 2^a extending from the cup like member 2. The rod 1^a is slotted as indicated at 54, through which passes a pin

55 carried by the sleeve 2^a so that lost motion can occur as required.

The moving head is by the agency of a nut member 4 and interposed washer 5 clamped to a diaphragm D which forms a false head to the vacuum chest C, the diaphragm being secured to the chest C by being clamped between the flared upper part 6 of the chest (which permits a relatively large diaphragm to be used) and a domed or dished head 7 thereof, thereby forming a chamber above the diaphragm separated from the chest by the diaphragm, the head 7 including a bearing 8 for the sleeve 2^a above referred to.

In the construction shown the conduit 28, Fig. 2, conveys atmospheric air to the chamber above the diaphragm D and suction is applied to the chest through the duct N.

By exhausting air from the chest C in which the container B has previously been disposed and admitting atmospheric air above the diaphragm, the moving head descends owing to the deflection of the diaphragm under the difference of pressure existing between that in the chest and atmosphere above the diaphragm.

The initial differences of pressure cause the downward movement of the presser member 1 and associated cup member 2; the member 1 applies the closure A to the container B and the presser member 1 is then arrested. The higher differences of pressure overcome the opposition of the spring 3 to the deflection of the diaphragm and the latter and the cup 2 move suddenly and relatively to the presser member 1 so that the cup is caused to pass the securing curls A¹ integral with the flange of the closure and bend them under the shoulder to secure the closure to the container in known manner.

According to the invention the time of exhaustion in the chest and of admission of atmospheric air above the diaphragm are independently regulated so that the suction on the chest C extracts from the container B any air therein and sterilizes the contents, and then while this condition is maintained atmospheric air is admitted through conduit 28 causing a fall of the diaphragm, the cap being secured to the container in two stages, first by the settling effect of member 1 and then by sealing

pressure accompanied by inturning of the curls A¹ by member 2.

The container being sealed, suction is applied above the diaphragm and cut off from the chest, atmospheric air being then admitted to the chest and the diaphragm then regains its normal position. The container B can then be removed and another replaced in position.

10 A platform P is utilized to supply containers to the chest.

Now, in order to control the connection of the chamber above the diaphragm and also the chest C to vacuum, and also to 15 atmospheric air, means are provided whereby after the platform P has been raised the pressures above and below the diaphragm are varied. To this end the platform P is attached to a spindle 16 slidably 20 and resiliently supported by spring 26 in a rack member 19 provided with teeth 56 with which meshes a pinion 57 which in turn is rotated on the operation of the lever 59 through the agency of the gear segment, 25 58.

As the lever is pulled down the rack member is raised up through the rack slide 17 carried on the arm 18 extending from the hollow column 13.

30 On the rack member 19 is a collar carrying adjustable tappets 19^a and 19^b, see Fig. 2, and the bearing member 17 is provided with wings or extensions 30, 31, in a plane at right angles to the arm 18, which extensions are bored to provide cylinders in which piston valves 24 and 29 operate. These pistons are spring-controlled as indicated in Fig. 2 and operable by the tappets 19^a and 19^b as the rack 19 rises. The cylinders of the valves are each tapped transversely to provide ports by which the cylinders are connected to the chest and to the chamber above the diaphragm respectively.

45 As shown in Fig. 2 the cylinder of the piston 29 is tapped for reception of duplex conduits 27 and 28 emanating from the chamber above the diaphragm, and the cylinder is also tapped at right angles as indicated at 27^a, Fig. 3, for connection to 50 pipe 61 as diagrammatically indicated in Fig. 3 by line 27^b.

In the position shown, the valve 29 uncovers the connection between 28 and 27^a, hence the chamber above the diaphragm is 55 subjected to the vacuum existing in column 13. Parallel to the tapping forming port 27^a, the cylinder is bored at 28^a to provide a connection to atmosphere, thereby when valve 29 is raised conduit 28 and port 28^a 60 communicate and atmospheric air enters the chamber above the diaphragm D. By adjusting tappet 19^b the movements of the valve 29 are regulated and consequently the deflection of the diaphragm precisely 65 timed.

The chest C and the cylinder of the valve 24 are connected by the duplex conduits 25 and N, of which the conduit 25 communicates with atmospheric air through the port 25^a (Fig. 3) bored in the cylinder 70 similarly as the port 28^a aforesaid.

The conduit N connects the chest through a port N' in the cylinder of the valve 24 to vacuum existing in column 13, the port N' being connected to the pipe 61 emanating 75 from the vacuum column 13, as diagrammatically shown by line N^a in Fig. 3.

By adjusting tappet 19^a the operation of the valve is regulated thereby timing precisely the commencement of the period during which the container is subjected to the 80 vacuum in column 13.

As the tappets 19^a and 19^b are independent, one of the other, a precise timing of the period of exhaustion may be effected 85 without interfering in the operation of the diaphragm to effect sealing of a container.

In the construction shown the hollow standard 13 functions as a reservoir for air at reduced pressure, and has a connection at 60 to a pump which exhausts the column, the pressure therein being communicated into the chest and above the diaphragm D by the pipe 61 in manner aforesaid. 90

It is well known that the reduction of pressure effected by pumps varies according to conditions, particularly at starting up and when the pumps are warm, and further that the sterilizing of different types of goods requires varying periods of treatment in vacuo to effect sterilization. The independent regulation of the valves 24, 29, by adjusting tappets 19^a, 19^b, affords such method of regulation. 95

The valve 29, in its normal position shown in Fig. 2, uncovers the connection between 28 and 27^a and thus subjects the chamber above the diaphragm to the vacuum existing in column 13. The general operation of the machine is as follows:— 100

On the handle 59 being pulled down, the platform P rises as previously explained, until the platform P closes the chest C. Immediately thereafter the valve 24 is engaged by the adjustable tappet 19^a carried by the rack member 19. This causes displacement of the valve uncovering the conduit N thereby opening communication with a port N' and the pipe 61 to vacuum, so that the container in the chest is subjected to reduced pressure. 115

Following this movement and with the continued rise of the rack member 19 at the expense of compressing the spring 26, the piston 29 is operated by the tappet 19^b so as to uncover the communication between the conduit 28 and atmosphere through the port 28^a thereby admitting air at atmospheric pressure above the diaphragm, and 125

causing the sudden deflection of the diaphragm with sufficient pressure to seal the container.

This effects in sequence the vacuumizing 5 of the container and the sealing of the container in the reduced atmosphere.

If, now, the arm 59 is returned to the normal (vertical) position shown in Fig. 1 the 10 first movement causes a fall of the rack and an extension of the spring 26, the fall of 15 the rack being sufficient to permit the fall of the valve 29 thereby again connecting the chamber above the chest D to the vacuum column 13 by the conduit 27, port 27^a and connection 61.

The continued fall of the rack member 19 permits the fall of the piston valve 24 and connects the chest C to atmospheric air through the conduit 25 and port 27^a. This 20 immediately releases the platform which then follows the continued downward movement of the rack member 19.

Referring now to the construction and support of the chest it will be noted that the 25 chest is provided with a cup 12 extending from the bearing portion 8 of the chest head which cup is carried in an upper arm 13^a extending from the column 13 above the lower arm 18 which supports the platform 30 P and rack 19.

The cup 12 is threaded for the reception of a screw cap 53 which seats on a packing 51^a at the bottom of the cup 12, thereby forming 35 an air seal over the extension 2^a of the moving head, where the said extension 2^a passes through the bearing 6.

What we claim is:—

1. In a vacuum sealing machine comprising 40 a sealing chest and a chamber separated therefrom by a flexible member carrying a presser member, separate valves for controlling the pressures in the chamber and in the chest, means for supplying containers to the chest, a gear means operating said supply means, and adjustable actuating means for said valves carried by said gear means.

2. In combination in a vacuum sealing 50 machine, a sealing chest, a chamber, a flexible member carrying a presser member and separating the chest and chamber, a platform, a gear means for reciprocating the platform to and from the chest, adjustable means for regulating the reduction of pressure in the chest operated by the reciprocating gear means after the platform has risen to the chest, and separate adjustable means actuated from said gear means for regulating the pressure in the chamber to cause a sudden actuation of the presser member.

3. In a vacuum sealing machine comprising 60 a sealing chest, a chamber separated therefrom by a flexible member carrying a presser member, a platform, and a gear means for reciprocating the platform to and from the chest, the combination of a valve

regulating the alternate admission of atmospheric air and air at reduced pressure to the chamber, a separate valve similarly controlling the pressure within the chest, an adjustable tappet for each of the valves, and 70 means carried by the said gear means for operating the tappets while the platform is reciprocated.

4. In a vacuum sealing machine comprising 75 a sealing chest and a chamber separated therefrom by a flexible member carrying a presser member, the combination with duplex connections from the chamber and duplex connections from the chest, one of each duplex connections forming a communication to atmosphere and the other a connection to air at reduced pressure, of a valve controlling the duplex connections from the chamber adapted to alternately close one and open the other, a separate and similarly 80 operated valve controlling the duplex connections from the chest, a platform, a gear means for reciprocating the platform to and from the chest, and adjustable tappets carried by the gear means for operating the 85 valves whereby the presser member is actuated.

5. A vacuum sealing machine comprising 90 a hollow column, a sealing chest supported by said column, a chamber on said chest, a flexible diaphragm separating said chamber and chest, an arm extending from said column below said chest, a vertical rack member guided in said arm, a platform resiliently supported by said rack member, means for 95 raising and lowering the rack member, adjustable tappets on the rack member, two valve cylinders, each having a connection to the column and an opening to atmosphere, valves therefor operable by said tappets, duplex connections between one valve cylinder and the chest, and duplex connections between the other cylinder and the chamber above the diaphragm, whereby the chest and chamber are each alternately connected to 100 the column and to atmosphere on the operation of the valves by the tappets.

6. In a vacuum sealing machine according 105 to claim 1, the presser member comprising a piston, a coaxial cup member, a lost motion connection between the piston and cup member, and a spring interposed between the piston and cup member.

7. A vacuum sealing machine comprising 110 a hollow column, an arm at the upper part thereof, a sealing chest supported in said upper arm, a chamber on said chest, a flexible diaphragm separating said chamber and said chest, a presser member carried by the diaphragm, a bearing in the chamber for 115 said presser member, an air seal over said bearing, an arm extending from the lower part of said column, and below said chest, a vertical rack member guided in said lower arm, a platform resiliently supported by said 120

125

130

rack member, means for raising and lowering the rack member, adjustable tappets on the rack member, two valve cylinders, each having a connection to the column and an opening to atmosphere, valves therefor operable by said tappets, duplex connections between one valve cylinder and the chest, and duplex connections between the other cylinder and the chamber above the dia-

phragm, whereby the chest and chamber are 10 each alternately connected to the column and to the atmosphere on the operation of the valves by the tappets.

In testimony whereof we affix our signatures.

JOSEPH H. HUXLEY.
